X-RAY GENERATOR

Michael J. Zunick, Chicago, Ill., assignor to General Electric X-Ray Corporation, Chicago, Ill., a corporation of New York

Application March 28, 1942, Serial No. 436,705

2 Claims. (Cl. 250—149)

My invention relates in general to electronics and has more particular reference to an X-ray generator having an anode providing an electron target comprising target material electroplated as a thin film on a suitable support.

An important object of the present invention resides in providing an anode having an electroplated electron target; a further object being to provide an anode for an X-ray generator having a target surface comprising a thin film of metal plated on a suitable base by electrochemical action, whereby the target comprises a deposit of substantially pure metal particularly well suited for analysis of materials by X-ray diffraction.

Another important object is to provide an X-ray tube for the analysis of materials by diffraction, the tube having an electron target of substantially pure metal capable of producing X-rays of known characteristics for use in diffraction analysis.

The foregoing and numerous other important objects, advantages and inherent functions of the invention will become apparent as the same is more fully understood from the following description, which, taken in connection with the accompanying drawing, discloses a preferred embodiment of the invention.

Referring to the drawing:

Figure 1 is a side view, partially sectionalized, of an X-ray tube embodying my present invention; and

Figures 2 and 3 are sectional enlarged views taken substantially along the line 2—2 in Figure 1 to show preferred forms of anode structure embodying the invention.

Analysis of materials may be accomplished by exposing the material to be analyzed to X-rays and observing the X-ray diffraction characteristics of the material on a sensitive screen or film.

The radiation of X-rays from a generator comprises a continuous, or "white," spectrum, the wave length and intensity distribution of which depends largely upon the operating potential of the generator and upon the characteristic "line" spectrum of the X-ray target material employed in the generator, every target material having its own characteristic line spectrum which is independent of the operating potential of the generator above a minimum voltage, which minimum voltage is also characteristic of the particular target material involved. Any target material may, of course, be employed for X-ray diffraction analysis, provided that the

material of the target, and hence its characteristic "line" spectrum, is known, otherwise, the lines caused by the target material in the spectrograph of the material being examined may be mistaken for lines supposedly caused by the material under examination.

The choice of a proper target material for X-ray diffraction analysis depends to a great extent upon the type of specimen being examined, the particular examination technique employed, and the kind of information sought; and it is obvious that, regardless of technique or the specimen under examination, a prerequisite for accurate analysis is accurate predetermination 15 of the spectrum characteristics of the target and hence of the X-rays produced by the generator. It will be apparent that, in order to facilitate X-ray diffraction analysis, it is desirable to provide generators having identical characteristics so 20 that examination technique and procedure need not be altered or modified to suit each individual X-ray source. It is, however, difficult to produce X-ray generators having identical spectrum characteristics, even where the generators include targets of identical material, for 25 the reason that the inclusion of impurities in the material of the target within the range of contamination tolerated in so-called commercially pure materials, may alter the spectrum characteristics of commercially identical targets to an appreciable extent.

In order to facilitate examination of materials by X-ray diffraction, I provide a target of desired material in substantially pure condition so 35 that generators having targets of like material will produce X-rays having substantially identical spectrum characteristics. To this end, I provide an anode comprising a base of suitable material for supporting the target, and I apply the target as a thin film of material by electroplating the target material on the base.

To illustrate the invention, I have shown on the drawing an X-ray tube 11 comprising an anode 13 and a cathode 15 in facing relationship 45 enclosed within an hermetically sealed and evacuated envelope 17, having suitable electrical connections extending through the envelope for supplying the anode and cathode with electrical power from a suitable external source.

The cathode 15 may comprise a head 19 supported and sealed upon a re-entrant envelope portion comprising a hollow stem 21. Conductors 23 for energizing the electron emitting filament 25 may extend through the stem 21. The 55 cathode end of the tube may be fitted with a

ferrule 28 carrying a base 29 for connecting the conductors 23 with a suitable external source of power for energizing the filament 25 for electron emission.

It will be noted that the filament is of elongated character and is supported in a groove 27 formed in the cathode head whereby electrons emitted by the filaments, when energized, will be focused upon the facing or target end 31 of the anode. The anode, near its target remote end, is formed with a shoulder to which is sealed a disk or washer 33 having an annular edge forming glass-to-metal seal 35 with the re-entrant portion 41 of the envelope, the anode having an extension 43 projecting outwardly of the envelope through the seal member 33 and being fitted with inlet and outlet conduits 45 for the circulation of a cooling fluid into the anode adjacent the target end thereof for cooling the same.

The envelope 11 preferably, though not essentially, comprises lead glass and is formed with conical embossments fitted with window-panes 47 of lime glass, beryllium, or other suitable window-pane material substantially transparent to X-rays, the windows 47 being located on the envelope opposite the target end of the anode in position to project X-rays emanating from the target end of the anode outwardly of the envelope. The cathode head also is preferably provided with a skirt 49 encircling the target end of the anode and formed with openings 51 for the transmission of useful X-ray beams from the anode to and through the windows 47. The tube also is preferably enclosed in an annular sleeve 53, which may comprise split parts suitably clamped together around the window portion of the envelope, the sleeve 53 being provided with openings 55 for receiving the window carrying envelope projections. If desired, the sleeve 53 may be formed of material opaque to X-rays for the purpose of confining therein all X-rays except the beams which emanate from the anode through the openings 51 in the cathode skirt, the windows 47, and the sleeve openings 55.

The anode 13 comprises a base of suitable material such as copper for supporting an electron target thereon at the target end 31 of the anode. I may employ any suitable target material, such as chromium, cobalt, nickel, iron, copper, manganese, or other metal susceptible of being applied to the metal anode base by an electroplating operation.

The base of the anode 13 may first be finished to desired size and shape and its target end 31 then treated in a suitable electroplating solution for a sufficient period of time to accomplish a deposit of target material of desired thickness in the form of a target layer 57 on the target end of the anode. The plated anode may then be buffed or otherwise polished prior to the assembly of the anode in operating position in the generator.

While it is exceedingly difficult, if not impossible, to obtain electron targets in "pure" condition, uncontaminated by infusion of other materials, where the anode is fitted with a target comprising a preformed block of target material, I find that, by applying the target material in accordance with my present invention, a target of pure metal is obtained; and, as a consequence, generators fitted with anodes having targets of like material, applied in accordance

with the teachings of my present invention, produce X-rays having identical spectral characteristics. Furthermore, since the target material is applied as a thin film, there is little, if any tendency of the material within the target area to fracture, curl up, or otherwise deteriorate in service, since the thin target layer is able to dissipate heat rapidly into the body or base of the anode 13; and consequently there is no wide temperature differential between the base attached and electron receiving surfaces of the target layer, and no appreciable internal stress set up within the layer, when the generator is in operation.

While the target layer 57 may be applied directly upon the base of the anode 13, I find it desirable, particularly in plating chromium as a target material on a copper base, to apply a foundation coating 59 of material such as gold or platinum, the target material 57 being then plated as a layer upon the previously plated layer 59. The foundation coating may be applied in any suitable manner, as by the electroplating process or other procedure for filming the foundation material on the base to form the layer 59. This multiple layer arrangement is of advantage where it is desired to employ an extremely thin target layer 57 or where the target material, as plated, has a tendency to be minutely porous. Where the material of the layer 57 has a tendency towards even slight porosity when plated, the material of the base may become effective through pores in the layer 57 and thus interfere with the spectral characteristics of X-rays generated at the anode. The effects of porosity of the target layer 57 may, of course, be obviated by making the layer sufficiently thick to preclude any possibility of pores therein. By applying a foundation layer of gold 59 or platinum, or other material having X-ray spectral characteristics that will not interfere with the X-ray spectrum of the target material in the layer 57, the effects of pores for spectrographic purposes is nullified for the reason that gold or platinum, if exposed to electron bombardment, of the velocity normally employed in the operation of X-ray generators, will not have their characteristic radiation excited, and hence if exposed within the target area, as through pores in the layer 57, have no appreciable effect upon the spectral characteristics of the resulting X-rays.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the form herein disclosed being a preferred embodiment for the purpose of illustrating the invention.

The invention is hereby claimed as follows:

1. An X-ray generator comprising a sealed envelope, an electron emitting cathode and a co-operating anode providing an electron target in said envelope, said cathode being formed and positioned to direct electrons upon said target for the generation of X-rays at the target, said anode comprising a base forming a target surface coated with a film of metal forming a base layer and metallic target material electroplated as a thin layer upon said coated target surface, the metal forming said base layer having X-ray spec-

torgraphic characteristics which do not interfere with the X-ray spectrum of the target material and the target material comprising one of the metals of the class consisting of cobalt, nickel, iron and manganese.

2. An X-ray generator comprising a sealed envelope an electron emitting cathode and a co-operating anode providing an electron target in said envelope, said cathode being formed and positioned to direct electrons upon said target

for the generation of X-rays at the target, said anode comprising a base forming a target surface, a film of gold forming a base layer coated on said target surface, and metallic target material electroplated upon said base layer, said target material comprising one of the metals of the class consisting of cobalt, nickel, iron and manganese.

MICHAEL J. ZUNICK.
